UNITED STATES PATENT OFFICE.

HENRY BERRY, OF BIRMINGHAM, CONNECTICUT.

DESIGN FOR A BOTTLE.

SPECIFICATION forming part of Design No. 16,311, dated October 6, 1885.

Application filed June 23, 1885. Serial No. 169,576. Term of patent 7 years.

To all whom it may concern:

Be it known that I, HENRY BERRY, a citizen of the United States, residing at Birmingham, in the county of New Haven and State of Connecticut, have invented a certain new and original Design for Bottles; and I do declare the following to be a full, clear, and exact description of the invention, such as will enable others skilled in the art to which it appertains to make and use the same, reference being had to the accompanying drawing, and to letters or figures of reference marked thereon, which form a part of this specification.

15 This design has relation to bottles for table-casters; and it consists in the novel form of the bottle, as herein shown and described.

In the accompanying drawing, the letter *a* designates the base of the bottle, which is of 20 nearly-cylindrical form, and terminates at the shoulder *b*, which rests on the caster-frame. The shoulder-expansion *z* extends vertically upward from the corner of the shoulder at *c*, and is rounded inward at its upper part, as indicated at *d*. From this point the body portion *e* extends upward in oval form, narrowing toward the neck portion, and terminating at the

rounded shoulder-expansion *g*, which extends from said rounded shoulder upward in conical form, gradually merging into the cylindrical neck *h*, which terminates in a flaring lip, *k*. In this design the general direction of the upper portion of the body-wall is followed in the conical portion of the neck above, and the stronger curve of the lower portion of said body is based upon the cylindrical expansion *g*, giving the bottle a graceful and well-balanced form.

Having described this design, what I claim, and desire to secure by Letters Patent, is— 40

The design for caster-bottles, having the base *a*, and the cylindrical shoulder-expansion *z*, rounded inward above, the oval body *e*, and the cylindrical neck having a conical lower part joining the body portion by a rounded shoulder, and terminating above in a flaring mouth, as shown and described.

In testimony whereof I affix my signature in presence of two witnesses.

HENRY BERRY.
